The ornamental design of a insert holder component, as shown.

DESCRIPTION

FIG. 1 is a perspective top view of the invention looking from the front of the insert holder component;
FIG. 2 is a perspective bottom view of the invention looking from below the insert holder component;
FIG. 3 is a top plan view of the invention;
FIG. 4 is a side view of the invention;
FIG. 5 is a bottom view of the invention; and,
FIG. 6 is a front view of the invention.
